FOREIGN PATENT DOCUMENTS

JP D1568594 2/2017

Primary Examiner — Kevin K Rudzinski*Assistant Examiner* — Amber J Rabie(74) *Attorney, Agent, or Firm* — Calfee Halter & Griswold LLP(57) **CLAIM**

The ornamental design of a guitar strap, as shown and described.

DESCRIPTION

FIG. 1 is a line drawing of a top/front/right/left perspective view of a guitar strap of the present design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof;

FIG. 7 is a left-side elevational view thereof; and,

FIG. 8 is a top/front/right enlarged perspective view of a specific portion of a guitar strap of the present design.

The broken lines showing portions of the guitar are for illustrative purposes only and form no part of the claimed design.

The dot dash broken lines used in FIG. 8 represent the boundaries of the enlarged partial view and form no part of the claimed design.
